UNITED STATES PATENT OFFICE.

JOHN C. HAGGART, JR., OF ALMA, MICHIGAN.

RADIATOR GUARD.

Application filed September 18, 1924. Serial No. 738,343.

This invention relates to a device for protecting radiators of motor vehicles and its object is to provide a structure for the purpose which is cheap to manufacture and may 5 be quickly and easily assembled.

A further object is to provide a construction whereby the device may be readily disassembled and repaired in case of accident, and whereby the device may very quickly 10 and easily be demounted from the motor vehicle in case it is desirable to remove it for the purpose of gaining free access to the radiator, engine or other parts for the purpose of replacement or repair.

15 The invention also consists in providing a structure having certain other new and useful features, all as hereinafter more fully described.

With the above and other ends in view the 20 invention consists in the matters herein-after set forth and more particularly pointed out in the appended claims, reference being had to the accompanying drawing in which

Fig. 1 is a front elevation of a device illustrative of the present invention and showing the same in place upon a motor vehicle;

Fig. 2 is a side elevation of the same with the adjacent parts of the motor vehicle 30 shown in dotted lines;

Fig. 3 is a perspective detail of parts of the device with the parts shown partly in section, and

Fig. 4 is a vertical sectional detail of a 35 lower portion of the device.

Guards for protecting the front of a radiator upon a motor vehicle have usually been so constructed and so secured in place upon the vehicle frame that they are not 40 conveniently and quickly detachable, and further, such constructions have usually been such that in case of accident and damage to the guard, it is very difficult to repair the damage.

45 The present structure comprises a series of vertically spaced apart guard bars 1 which are preferably formed from flat stock and are of rectangular shape in cross section. To hold these bars in assembled position and in spaced relation, a rod 2 is passed through a hole in each of the bars 1 near their upper ends and sleeved upon this rod between adjacent bars is a series of short tubular sleeves 3. A short tubular spacer 50 member 4 is sleeved upon the rod in contact with the outer side of each of the outer

bars 1 of the assembly and brace rods 5 are provided with openings in their upper ends to receive the rod and are held upon the ends of the rod in contact with the spacers 60 4 by means of nuts 6 engaging the screw-threaded ends of the rod 2. The bars are secured in assembled and spaced relation adjacent their lower ends by means of a rod 7 which passes through openings in the several bars and upon which rod is sleeved a series of spacer sleeves similar to the sleeves 3. Adjacent its ends the rod 7 is screw-threaded as at 8 to receive nuts 9 adapted to engage the outer face of the outer bars 70 of the assembly and thus clamp all of the bars together upon the rod and spaced apart by the sleeves 3. The end portions 17 of the rod 7 are of reduced diameter to engage sockets or recesses in the inner ends of the 75 screw-plugs 10 which plugs are externally screw-threaded to engage screw-threaded openings in the side frame members 11 of the chassis frame. The outer ends of these plugs 10 are each formed with a hexagonal 80 head 12 for the application of a wrench thereto so that the plugs may be screwed inwardly to firmly engage the end portions 17 of the rod 7 and thus securely hold and rigidly support the lower end portion of the 85 guard between the side frame members 11 of the vehicle frame.

To rigidly brace and support the upper end of the guard forwardly of and in spaced relation to the forward side of the radiator which is indicated at 13, the brace members 5 which are securely attached to the ends of the rod 2, are provided, said braces being preferably curved in the direction of their length to extend rearwardly at the sides of 90 the radiator where they are secured at their lower ends to brackets 14 riveted or otherwise permanently secured to the upper sides of the frame members 11, said brackets being provided with upwardly extending ears 15 95 which are spaced apart and provided with openings to receive bolts 16 and between which ears the lower flattened end portions of the braces 5 are secured by these bolts 100 passing through openings in these end portions of the braces.

A guard of this character may be quickly 105 assembled or taken apart as it consists of a series of flat bars which are strung upon top and bottom rods passing therethrough with the tubular spacers between the bars. By removing the nuts 6 and 9 from the ends 110
